UNITED STATES PATENT OFFICE.

CHARLES L. PLUNKETT, OF BROOKLYN, NEW YORK, ASSIGNOR TO AMERICAN COUCH COMPANY, OF BROOKLYN, NEW YORK, A CORPORATION OF NEW YORK.

COUCH-BED.

986,406.

Specification of Letters Patent. Patented Mar. 7, 1911.

Application filed December 31, 1910. Serial No. 600,255.

To all whom it may concern:

Be it known that I, CHARLES L. PLUNKETT, a citizen of the United States, residing at Brooklyn, in the county of Kings and 5 State of New York, have invented certain new and useful Improvements in Couch-Beds, of which the following is a specification.

This invention relates to improvements in 10 couch beds, the object of the invention being to provide a couch or couch-section having a storage receptacle and in which the use of the side bars heretofore deemed necessary may be dispensed with, whereby the structure 15 may be very much simplified, the weight reduced and the expense of manufacture lessened, while the structure will be as durable and as strong as those structures in which the side bars were used.

20 A further object of the invention is the provision of an improved means for supporting one part or half of the spring mattress of one of the sections of the bed whereby the same will be maintained level with the 25 other part thereof.

Heretofore in couch beds it has been necessary, owing to the tension of the metallic fabric connected to the end frames forming each section of the bed, to provide side bars 30 for maintaining the end frames apart. These side bars are heavy, since they must be made of tubing or angle iron, and necessarily increase the cost of the structure, but it has not been considered practicable to dispense with them. In the present improvement, however, I provide a section of the 35 bed with a storage receptacle so located that it will take the place of the side bars and thus permit such side bars to be dispensed with, and which storage receptacle, in the preferred form of the improvement, will be maintained in position by the tension of the metallic fabric, thus also obviating the necessity of providing a special means for 40 securing the storage receptacle in place.

In the present improvement the end frames carrying the storage receptacle comprise transverse members and supporting members or legs adapted to rest upon the 45 floor, so that the storage receptacle is wholly supported by and suspended between the end frames, which are not of rudimentary form, and the present construction is therefore an important improvement in several respects. 50

temporaneously pending allowed application, Serial No. 465,631, filed December 2, 1908.

In the drawings accompanying and forming part of this specification, Figure 1 is a perspective view of one form of this improved couch bed, comprising a pair of telescoping sections with a part of the fabric and the sectional or folding mattress removed; Fig. 2 is a transverse view, with the storage receptacle shown in section, of this form of couch bed open; Fig. 3 is a transverse sectional view of that section of the couch bed carrying the storage receptacle; Fig. 4 is a detail view of the spring mattress 70 of the shiftable section; and Fig. 5 is a detail sectional view illustrating the manner of connecting one part of the spring mattress of the shiftable section.

Similar characters of reference indicate 75 corresponding parts throughout the figures of the drawings.

In the present improvement the couch is shown comprising a pair of sections, one comprising a main or stationary section 2 having a pair of end frames 3 and 4, each comprising a transverse member 5 shown herein as horizontal, having legs or supports 6, these transverse members having attached thereto and stretched therebetween a spring 80 mattress or metallic fabric 7. For connecting the end frames together so as to prevent the spring mattress from drawing them toward each other suitable side bars 8 are provided. The other section, herein designated as the shiftable or sliding section 9, likewise comprises a pair of end frames 10 and 11, each comprising a transverse member 12 shown herein as horizontal, having legs or supports 13 constructed to rest upon 90 the floor. Supported by this shiftable section, preferably by brackets 14 carried by the legs, is a storage receptacle 15 having a swinging cover 16.

The stuffed mattress supporting means in 100 the present instance comprises a metallic fabric or spring mattress 17 stretched under tension between the end frames, one part or half, as 18, thereof being connected to the horizontal members 12 while the other half 105 or part 19 thereof is connected in the present improvement to a pair of angle irons 20 pivotally secured at the inside of the horizontal members 12, for which purpose the horizontal members 12 have riveted thereto 110

brackets 12', see Fig. 5, to which the members 20 are pivotally connected at the inner side of the horizontal angle members 12. In my prior application, Serial No. 473,812, filed January 23, 1909, these angle irons 20 are pivotally secured to the outside of the horizontal members, in consequence of which the helical springs would necessarily rest upon the tops of the horizontal members, 10 and owing to their diameter the spring mattress could not be entirely level with the non-swinging part thereof if it was attached directly to the end frames, and in consequence this part of the mattress had to be 15 attached to separate angle iron members which were riveted to the end frames; but by means of the present improvement it will be observed that the two parts of the spring mattress for the shiftable section may be entirely level, while the fixed part thereof may 20 be connected directly to the members 12 without the necessity of using additional angle iron members on top thereof. The outer ends of these pivoted angle iron members will rest upon suitable supports 21, carried by the legs, when the same are down. The cover 16 is linked to this swinging portion 25 of the mattress by suitable links 22, a pair thereof being shown, so that on raising one half of the mattress the cover of the 30 storage receptacle will also be lifted.

The members 20 forming a part of the swinging half of the spring mattress are connected at their outer ends by a drop 35 formed bar 23 for preventing the same from being drawn toward each other by the tension of the fabric, and to this bar the cover of the storage receptacle is connected. The storage receptacle being placed upon its supports and the spring fabric attached to the 40 horizontal members of the end frames, it will be observed that the tendency of the tensioned fabric to draw the end frames toward each other, which is also increased 45 by the weight of the occupant, is prevented by the storage receptacle, which thus is utilized to take the place of the side bars heretofore deemed necessary, thus dispensing with such side bars, the spreading of the 50 legs being prevented by means of tension strips 24 connected thereto.

When the shiftable section is formed without the swinging half of the spring mattress it is obvious that the drop formed bar may 55 be also dispensed with, it being merely necessary then to form the front of the box so that it can swing up or down.

By the present improvement it will therefore be observed that I am enabled to provide 60 a couch bed with a storage receptacle held in position by the angle iron formation of the legs and the tension of the fabric, since no other means is necessary to hold the box in position against displacement than 65 the tension of the fabric, other than suit-

able supports or brackets located at the underside thereof to support the weight of the box, thus obviating the necessity of fastening devices for securing the box to the end frames, and as the box is effective to prevent the drawing of the end frames toward each other I am also able to do away with the use of side bars heretofore deemed necessary. 70

When the present improvement is applied 75 to a couch such as that shown in the drawing the two sections may be linked together by means of links 30 connected with a swinging bar 31, by means of which the shiftable section may be opened and closed, and this 80 swinging bar may carry a sectional mattress which will be also opened and closed simultaneously with the swinging of the bar. 75

I claim as my invention:

1. A couch bed comprising a pair of end 85 frames consisting of transverse members and legs adapted to rest upon the floor, a storage receptacle supported wholly by said end frames and itself forming the means for maintaining the end frames spaced apart, 90 and yielding mattress supporting means carried by said end frames above the storage receptacle. 95

2. A couch bed comprising a pair of end frames consisting of transverse members and 100 legs adapted to rest upon the floor, a storage receptacle supported wholly by said end frames and itself forming the means for preventing movement of the end frames relatively to each other, and a spring mattress 105 stretched under tension and connected to said end frames and effective to hold the storage receptacle in place between the end frames. 110

3. A couch bed section comprising a pair 115 of end frames each consisting of a transverse member and a pair of angle iron formed legs adapted to rest upon the floor, a storage receptacle supported wholly by the angle iron legs with the corners of the receptacle overlapped by said legs and itself forming the means for preventing the end frames from being drawn together by the tension of the fabric, a spring mattress stretched under tension and connected to said end frames and effective to draw the end frames toward each other and so hold the storage receptacle in place between the end frames, and means for preventing the spreading of the end frames. 120

4. A couch bed comprising a pair of end frames comprising transversely extending members and legs adapted to rest upon the floor, a storage receptacle supported wholly by said end frames and itself forming the 125 means for preventing movement of the end frames relatively to each other, and a spring mattress stretched under tension and connected to said end frames and effective to hold the storage receptacle in place between 130

the end frames, said mattress being formed as a two-part fabric, one part liftable relatively to and above the other and also above the transversely extending members of the end frames, said liftable part being pivotally connected to the end frames at the inside thereof whereby the mattress may be entirely level.

5. A couch bed section comprising a pair of end frames consisting of transverse members and legs adapted to rest upon the floor, a storage receptacle supported wholly by said end frames and itself forming the means for preventing movement of the end frames relatively to each other, a spring mattress stretched under tension and connected to said end frames and effective to hold the storage receptacle in place between the end frames, said mattress being formed as a two-part fabric, one part liftable relatively to and above the other, said liftable part being pivotally connected to the end frames at the inside thereof whereby the mattress may be entirely level, a bar connecting the ends of the liftable fabric, a cover hinged to said storage receptacle, and a link or links connecting said cover with said bar.

6. A couch section comprising a pair of end frames consisting of transverse members and legs adapted to rest upon the floor, a metallic fabric stretched under tension therebetween, a part thereof liftable relatively to and above another part thereof and also above such end frames and having members at its ends pivotally connected to the inside of the end frames of the section whereby the fabric may be entirely level.

7. A couch bed comprising a pair of telescoping bed sections, one shiftable relatively to the other, the shiftable section comprising a pair of end frames consisting of transverse members and legs adapted to rest upon the floor, a storage receptacle supported wholly by said end frames and itself forming the means for maintaining the end frames spaced apart, and a spring mattress stretched under tension and connected to said end frames for maintaining the storage receptacle in position.

50 8. A couch bed comprising a pair of telescoping bed sections, one shiftable relatively to the other, the shiftable section comprising a pair of end frames consisting of transverse members and legs adapted to rest upon the floor, a storage receptacle supported wholly by said end frames and itself forming the means for maintaining the end frames spaced apart, and a spring mattress stretched under tension and connected to said end frames for maintaining the storage receptacle in position, said mattress having a part thereof liftable relatively to and above another part thereof and also above the end frames, said liftable part being pivotally connected at the inside of the end

frames whereby the mattress may be entirely level.

9. A couch bed comprising a pair of telescoping bed sections, one shiftable relatively to the other, the shiftable section comprising a pair of end frames consisting of transverse members and legs adapted to rest upon the floor, a storage receptacle supported wholly by said end frames and itself forming the means for maintaining the end frames spaced apart, a spring mattress stretched under tension and connected to said end frames for maintaining the storage receptacle in position, said mattress having a part thereof liftable relatively to and above another part thereof and also above the end frames and said liftable part being pivotally connected at the inside of the end frames whereby the mattress may be entirely level, a swinging cover for said storage receptacle, a bar extending lengthwise of the swinging mattress part, a link or links connecting said cover with said bar whereby the swinging part of the mattress and cover may be simultaneously lifted, and means for preventing the spreading of the end frames.

10. A couch bed comprising a pair of telescoping bed sections, one shiftable relatively to the other, the shiftable section comprising a pair of end frames consisting of transverse members and legs adapted to rest upon the floor, a storage receptacle supported wholly by said end frames and itself forming the means for maintaining the end frames spaced apart, a spring mattress stretched under tension and connected to said end frames for maintaining the storage receptacle in position, said mattress having a part thereof liftable relatively to and above another part thereof and said liftable part being pivotally connected at the inside of the end frames whereby the mattress may be entirely level, a swinging cover for said storage receptacle, a bar extending lengthwise of the swinging mattress part, a link or links connecting said cover with said bar whereby the swinging part of the mattress and cover may be simultaneously lifted, means for preventing the spreading of the end frames, and means for shifting the shiftable section to form a couch or a double bed and adapted to carry a sectional mattress which may be opened or closed simultaneously with the shifting of the shiftable section.

11. A couch section comprising a pair of end frames consisting of transverse members and legs adapted to rest upon the floor, a yielding mattress supporting means supported by the end frames, a part liftable relatively to and above another part thereof and also above the end frames and having a lengthwise extending bar connecting the ends of said liftable part, a storage re-

ceptacle carried by said section and having a shiftable cover, and a link or links carried by said cover and bar whereby on the swinging of the liftable part of the mattress the 5 cover will be simultaneously shifted.

12. A couch bed comprising a pair of end frames consisting of supports and horizontal members, and a two-part suspensively supported metallic fabric supported by the end 10 frames, one a fixed part connected directly to said horizontal members by helical

springs and the other a liftable part pivotally secured to said horizontal members for swinging movement above the fixed part of said fabric.

Signed at 1822 Park Row Building, New York, N. Y., this 30th day of December, 1910.
